(57) CLAIM

The ornamental design for a detachable-face-shield dust-proof clothing, as shown and described.

DESCRIPTION

FIG. 1 is a perspective view of a detachable-face-shield dust-proof clothing showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is another perspective view thereof.

Any broken lines represent an internal boundary of the design; the line itself and the area within form no part of the claim.

1 Claim, 9 Drawing Sheets
